2 SHEETS—SHEET 2.

UNITED STATES PATENT OFFICE.

EDMOND KUHN AND ARTHUR H. FITZPATRICK, OF EAST ORANGE, NEW JERSEY.

PICTURE-EXHIBITING MACHINE.

1,100,892.

Specification of Letters Patent. Patented June 23, 1914.

Application filed April 8, 1913. Serial No. 759,684.

To all whom it may concern:

Be it known that we, EDMOND KUHN and ARTHUR H. FITZPATRICK, both citizens of the United States, and both residents of East Orange, county of Essex, and State of New Jersey, have made and invented certain new and useful Improvements in Picture-Exhibiting Machines, of which the following is a specification.

10 Our invention relates to an improvement in what are generally known and referred to as moving picture machines, the object of the invention being to so construct a machine of this character that it may be used 15 for public exhibition, or so constructed that it may be utilized or employed as a toy.

A further object of the invention is to devise a machine of this character which may be employed to exhibit opaque pictures 20 by throwing them upon a screen, the pictures to be exhibited individually, or in rapid succession, to give the impression of motion; in other words, to devise a machine wherein may be exhibited individual pictures, as, for 25 instance, picture postals, or a series of pictures in rapid succession whereby to secure the same effect or impression as is obtained in the ordinary moving picture machine, and wherein a transparent tape or film is used.

30 A further object of the invention is to provide a machine of this character which will be simple in construction, cheap to manufacture, and simple to operate.

With these and other ends in view, the invention consists in certain novel features of construction and combinations of parts as will be hereinafter fully described and pointed out in the claims.

In the accompanying drawing, Figure 1 40 is a view of our improved picture exhibiting machine, partly in section and partly in elevation; Fig. 2 is a plan view thereof, a portion of the top being broken away in order to more clearly show the operating mechanism; Fig. 3 is a view taken on the line 3—3 45 of Fig. 2, looking in the direction of the arrow; Fig. 4 is a view taken on the line 4—4 of Fig. 3, looking in the direction of the arrow; Fig. 5 is a detail view, in section, 50 showing a portion of a card of relatively greater width than the roller or carrier; Fig. 6 is a sectional view taken through one of the cards or pictures and holder; Fig. 7 is a sectional detail view showing the method of 55 holding the carrier upon the shaft, the ad-

justment of the parts being such that the roller may be removed from said shaft.

Referring to the drawings, the reference numeral 8 designates a suitable casing or hood of any form and within which is located a suitable illuminating device shown as comprising two incandescent electric lamps 9, although other illuminating means, such, for example, acetylene or gas mantle lamps, may obviously be employed so long as sufficient illumination of the pictures is secured. The interior of the casing will be equipped with suitable reflectors, as shown at 10, for concentrating the light from the lamps upon the pictures to be exhibited, which pictures are located at the rear of the lamps as shown in Fig. 1. The front portion of the casing is provided with a suitable lens carried in a telescopic tube 11, as is usual in picture exhibiting devices, and the purpose of which is to project the pictures upon a screen located at a considerable distance from the exhibiting device as will be understood.

The rear and bottom walls of the casing 80 8 are provided with openings 12, 13, in order to permit the picture carrying mechanism of the device to be placed in proper position relative to the lamps. This picture carrying mechanism comprises an upright hollow pedestal 14 supported from the base 15 of the device, and within which a standard 16 is vertically adjustable, which standard may be secured in its adjusted positions by means of a set screw 17. The standard 16 carries a bracket 18 at its upper end, having suitable bearings within which an operating shaft 19 is supported, which shaft carries a worm 20 and is operated by a suitable handle 21. The bracket 18 is also provided with other bearings within which a horizontal shaft 22 is supported, which shaft is provided with a pinion in engagement with the worm 20 as best shown in Figs. 2 and 3.

Supported by the horizontal shaft 22 and 100 rotating therewith is a picture carrying reel comprising a hub 23 and heads or disks 24, one at each end of said hub, which heads are provided each with a circumferentially extending series of holes 25 which form 105 bearings for the ends of a plurality of picture holding elements, each of which in turn supports a picture to be exhibited by the device. The reel is shown as held in place upon the shaft by means of a swinging 110

latch 26 which may be turned in line with the shaft, as shown in dotted lines, Fig. 3, to permit the reel to be placed on the shaft or removed therefrom when it is desired to substitute a new reel for the reel already in the machine. When the reel is in place the latch occupies a position extending across the shaft, as shown in Figs. 1 and 3, and abuts against a pin 27 to thereby prevent the reel from slipping, the reel being held against the latch by means of a spring 29.

Figs. 5 and 6 illustrate the preferred construction of the picture carrying elements which we have designated by the reference numerals 30, and each of which is shown as comprising a rod 31, the ends of which enter the holes 25 above referred to, and a clip 32 shorter than, and partially surrounding, said rod and secured thereto, the jaws 33 of which clip serve to grasp and hold a picture 34 as shown in Fig. 6. One of these jaws is shown as having a rib 35 which forms a stop against which the edge of the picture abuts, and whereby the extent to which the edge of the picture enters the clip is regulated, and uniformity in this respect secured. It will be seen that the jaws 33 of the picture holding members extend beyond the periphery of the disks of the reel, which feature permits the use of pictures wider, as shown in Fig. 5, than the reel, as well as narrower than the reel, as will be understood. The construction of the picture holding element permits the pictures 34 to be changed at will, as they have merely to be pulled from the holders and other pictures placed therein, which is a feature of importance especially in exhibiting individual pictures such as photographs, picture postal cards, etc. At the same time, the pictures may, if desired, be permanently secured in the clips as by forcing the jaws into firm contact with the edge of the pictures, in which case the pictures may be changed by removing one of the end disks of the reel, and replacing the original pictures carried thereby by others. Extending upward from the bracket 18 is an arm 36, the upper end of which carries an adjustable stop 37, the same being slotted as shown at 38 and held in its adjusted positions by means of a threaded knob or screw 39. The free end of this stop is bent downward, as shown at 40, Fig. 4, and adapted to engage the upper edges of the pictures and hold them temporarily in a vertical position, as shown.

The pictures 34 used in our device are stiff, as distinguished from flexible, and are opaque as distinguished from transparent pictures. The backs of the pictures, being white, each picture after it has been released from the stop 37 and permitted to fall, as will be understood from Figs. 1 and 4, serves as a reflector to assist in concentrating the light upon the picture which occupies a vertical position, thus securing a more intense illumination of the picture being exhibited. It will be further obvious that because of the relative position of the free end of the stop 37 and the axis of the reel, the said free end lying in front of a vertical plane passing through the axis of the reel, the picture occupying a vertical or substantially vertical position is moved rapidly in a downward direction to release its upper edge from the stop, after which it falls by gravity as the next picture comes into a vertical position. The pictures are thus not bent or flexed as is usual in picture exhibiting devices, and the picture being exhibited is in a single plane throughout its entire area, as distinguished from curved. The pictures projected upon the screen are thus less distorted than would be the case if the pictures 34 were bent or curved, and released from the stop 37 by a snapping action; in consequence of which they may be made of heavier material, and thus rendered more durable than would be the case if they were necessarily bent or curved while being exhibited.

The bracket 18 is made vertically adjustable for the double purpose of adapting the device for use with pictures of different heights, within the limits imposed by the structural features of the machine, and of securing a proper position of the projected pictures upon a screen. It will be obvious, referring to Figs. 1 and 4, that pictures varying considerably in their vertical dimension or height may be used by properly adjusting the stop 37. The pivotal support of the picture about to be released will obviously be farther down the front or left-hand side of the reel the greater the height of the picture, but the stop 37 may obviously be so adjusted by moving it to the left or right that the picture being exhibited, which is the one about to be released, will occupy a vertical position whatever may be its vertical dimension, within the limits imposed by the structural features of the machine. The said stop may also obviously be adjusted in such a way that the picture being exhibited will occupy a slightly inclined position, if in the final adjustment of the machine it be found that a clearer picture is thereby secured upon the screen. After adjusting the stop to secure a proper release of the pictures carried by the reel it may occur that the picture is not properly positioned upon the screen, in which case the entire reel may be moved vertically to bring the projected picture in a proper position upon the screen. The stop 37 may then, if desired, be readjusted, as a slight variation of the position of the upper edge of the picture, which position obviously determines the inclination of the picture being exhibited, will often result in a clearer or better defined picture upon the screen.

It will be obvious that the reel may be operated slowly, and individual pictures exhibited, which pictures may be changed at a minimum of trouble. At the same time if 5 the reel be equipped with a series of pictures and operated rapidly, the well-known moving picture effect will be produced upon the screen upon which the pictures are projected. When thus used, it will be obvious that the 10 reel may be driven by means of a suitable motor, instead of manually as in the device illustrated in the drawings.

From the foregoing it will be understood that our improved device may be elaborately constructed, and of a size to be used in public exhibitions, the reel being such as to permit of a large number of pictures to be secured thereto, or the device may be constructed of a smaller size and comprising in 20 part a reel designed to carry a less number of pictures, and which latter device can be manufactured and sold at a comparatively small cost. Furthermore, the machine is capable of containing and exhibiting opaque 25 pictures of different sizes, such as photographs, post card, etc., easily attached to or detached from the reel or carrier, and again, without change or alteration in the structure, may be employed with a series of pictures 30 to be substituted for the individual pictures, and when rapidly and in succession reflected on the screen, give the same impression as the ordinary picture exhibiting machine employing a long transparent 35 strip or film.

Having thus described and explained our invention, we claim and desire to secure by Letters Patent:

1. In a picture exhibiting machine, a vertically adjustable bracket having a plurality of bearings; a support for said bracket; a horizontal shaft one end of which is supported in bearings in said bracket and the other end of which shaft is unsupported; a pinion carried by said shaft; a driving shaft supported in bearings in said bracket and which shaft extends at right angles to said first-mentioned shaft and is provided with a worm in engagement with said pinion; a picture carrying reel supported by and driven from said horizontal shaft; a plurality of opaque inflexible pictures carried by said reel and the inner ends of which are pivotally secured thereto; a stop located above said reel and adapted to engage the outer ends of said pictures and hold each picture temporarily in a vertical position; and means for illuminating the picture being exhibited.

2. In a picture exhibiting machine, a sup-

porting base; a pedestal carried by said base; a standard supported by said pedestal and vertically adjustable relatively thereto; a bracket carried by said standard and having a plurality of bearings; a horizontal shaft one end of which is supported in bearings in said bracket and the other end of which is unsupported, and the free end of which shaft is provided with a swinging latch; a pinion carried by said shaft; a driving shaft supported in bearings in said bracket and which shaft is provided with a worm in driving engagement with said pinion; a picture carrying reel supported by and driven from said horizontal shaft and one end of which reel is in engagement with said swinging latch; a spring surrounding said horizontal shaft and acting against the other end of said reel; a plurality of opaque inflexible pictures carried by said reel and the inner ends of which are pivotally secured thereto; a stop located above said reel and adapted to engage the outer ends of said pictures and hold each picture temporarily in a vertical position; and means for illuminating the picture being exhibited.

3. In a picture exhibiting machine, a bracket having a plurality of bearings; a support for said bracket; a horizontal shaft one end of which is supported in bearings in said bracket and the other end of which shaft is unsupported, and the free end of which shaft is provided with a swinging latch; a driving shaft supported in bearings in said bracket and which shaft extends at an angle to said first-mentioned shaft; means whereby said horizontal shaft is driven from said driving shaft; a picture carrying reel supported by and driven from said horizontal shaft and one end of which reel is in engagement with said swinging latch; a spring surrounding said horizontal shaft and acting against the other end of said reel; a plurality of opaque inflexible pictures carried by said reel and the inner ends of which are pivotally secured thereto; a stop carried by said bracket and extending above said reel and the free end of which is adapted to engage the outer ends of said pictures and hold each picture temporarily in a vertical position; and means for illuminating the picture being exhibited.

Signed at Orange, in the county of Essex, and State of New Jersey, this 4th day of April, 1913.

EDMOND KUHN.

ARTHUR H. FITZPATRICK.
